(57) CLAIM

The ornamental design for a combined light and shelf, as shown and described.

DESCRIPTION

FIG. 1 is a perspective view of a combined light and shelf showing my new design.

FIG. 2 is a top plan view thereof.

FIG. 3 is a side view thereof.

FIG. 4 is an end view thereof; and,

FIG. 5 is a bottom plan view thereof.

The broken lines in FIGS. 1 and 5 illustrate environmental elements and form no part of the claimed design.
